UNITED STATES PATENT OFFICE.

PETER F. GREENWOOD, OF PHILADELPHIA, PENNSYLVANIA.

DESIGN FOR A HORSESHOE.

SPECIFICATION forming part of Design No. 18,215, dated March 27, 1888.

Application filed January 16, 1888. Serial No. 260,953. Term of patent 7 years.

To all whom it may concern:

Be it known that I, PETER F. GREENWOOD, a citizen of the United States, and a resident of Philadelphia, Pennsylvania, have invented 5 a new and original Design for a Horseshoe, of which the following is a specification.

My design for a horseshoe is fully illustrated in the accompanying drawing, the view in which is a face view of the shoe.

10 The shoe is wide and rounded at the toe portion and diminishes in width as it nears the heel portion. The two side portions, *a a*, of the shoe gradually increase in width from the heels *b b* to the toe *d*, and have at each side grooves *e e* and deep recesses *f*. The shoe is 15 provided at the toe with an enlargement, *i*, the edges *c c'* of which follow the contour of the

shoe, while the edges *g g'* taper toward the center of the shoe, and at the heels *b b* are projections *b' b'*. 20

I claim—

The herein-described design for a horseshoe having the outline illustrated, comprising the two side portions, *a a*, an enlargement, *i*, at the toe portion, with edges *c c'*, following the contour of the shoe, and tapering sides *g g'*, all substantially as shown and described. 25

In testimony whereof I have signed my name to this specification in the presence of two subscribing witnesses.

PETER F. GREENWOOD.
